UNITED STATES PATENT OFFICE

2,494,226

PESSARY

Fred M. Bley, Chicago, Ill., assignor to David E. Yeoman and Florence Yeoman, St. Charles, Ill.

Application August 7, 1946, Serial No. 688,824

2 Claims. (Cl. 128—131)

1

This invention relates to pessaries and is in the nature of an improvement on the device shown and described in my prior Patent No. 1,917,870, dated July 11, 1933.

The principal object of the present invention is to improve on the construction of pessaries in general, to improve upon the shape thereof, and to provide an improved connection between the body portion thereof and the end plate.

Another object is to eliminate the use of solder or other brazing material for connecting the body portion to the end plate.

Another object is to enclose the connecting means in the end plate so that there shall be no likelihood of injury to the patient from the connecting means.

With these and other objects and advantages in view, this invention consists in the several novel features of construction, arrangement and combination of parts hereinafter fully described, and more particularly defined in the appended claims.

The invention is clearly illustrated in the accompanying drawings, in which:

Fig. 1 is a side elevation of a pessary embodying a simple form of the present invention, and illustrating its application in a uterus.

Fig. 2 is an end elevation of the inner member of the end plate, illustrating its shape at one stage of its formation.

Fig. 3 is a cross-section taken on the level 3—3 of Fig. 2;

Fig. 4 is an end elevation of the member seen in Fig. 2, but illustrating the same in a more developed form;

Fig. 5 is a cross-section taken on the line 5—5 of Fig. 4;

Fig. 6 is an end elevation of the outer member of the end plate;

Fig. 7 is a cross-section taken on the line 7—7 of Fig. 6;

Fig. 8 is a side elevation of the body member of the device, illustrating the same at one state of its construction;

Fig. 9 is a similar view of the completed body member;

Fig. 10 is a fragmental longitudinal section of one end portion of the body member;

Fig. 10^A is a plan of the end coils seen in Fig. 10;

2

Fig. 11 is a view partly in side elevation and partly in vertical cross-section of a fragment of the body member and the inner member of the end plate, illustrating the connecting means between the two;

Fig. 12 is an end elevation of the parts seen in Fig. 11; and

Fig. 13 is a view partly in side elevation and partly in central longitudinal section of the completed device.

Figs. 2 to 13 are upon enlarged scales.

Referring to said drawings, which are merely illustrative of one embodiment of the invention, the reference character 15 designates the inner member of an end plate 16 (see Figs. 1, 4, 5, 11 and 13) and 17 designates the outer member of the end plate (see Figs. 6, 7, and 13).

In the course of forming the inner member 15, a blank is given the form illustrated in Figs. 2 and 3, preferably with suitable forming dies. The blank is dished and formed with a marginal flange 18. Subsequently the dished part of the member 15 is drawn deeper (see Fig. 5) and is pierced centrally to form an aperture 19, and the metal around the aperture is extruded to form a neck 20, which is notched inwardly from the edge to form ears 21.

The outer member 17 of the end plate 16 also dished, and is centrally apertured as at 22, and a bail 23 is struck up from the metal of the outer member in an inward direction and bridges the aperture 22. The bail provides means whereby a suitable inserting instrument may be used for inserting and removing the pessary into and from the uterine cavity. In the completed device, the flange 18 is clenched upon the edge portion of the outer member 17, thereby uniting the two members, as seen in Fig. 13.

The body member 24 of the device is formed of a filament of flexible material such as wire, wound into helical form to provide the wall of a hollow body member of which the convolutions or coils are spaced apart slightly to enable secretions to enter the interior of the body member and be discharged through the apertured end plate 16.

The major portion 25 of the body member may be formed with a flaring base portion 26^A, from which the body member may taper slightly to

ward its other end, at 26 it bulges outward slightly and its end portion 27 is made substantially conical to facilitate insertion of the device into the uterine cavity.

In constructing the body member, the ends 28, 29 (see Fig. 8) may be left projecting from the ends of the body member. Subsequently the end 28 is turned into the adjacent open end of the conical portion and bent down with its extremity, terminating within the next adjacent coil, as seen in Figs. 10 and 10^A, to provide a smooth end for the conical end portion 27. The protruding end 29 is cut off to leave an end coil 30, which is employed for connecting the body member with the inner member 15 of the end plate.

In assembling the body member 26 with the inner plate member 15, the end coil 30 is inserted from the concave side through an aperture 31 in the dished wall of the inner plate member, and is turned around the neck 20 of the inner plate member. With suitable dies, the ears 21 are then curled over the end coil and clenched down upon it, thereby securely fastening the body member and inner plate member together.

Subsequently the two end plate members are assembled by placing the marginal edge portion of the outer plate member 17 against the convex side of the inner plate member 15, and with suitable dies the flange 18 is clenched down upon the marginal edge portion of the outer plate member (see Fig. 13) thereby rigidly fastening the two plate members together to form the complete end plate 16.

It is to be observed that the connecting means between the body member and end plate are wholly contained in the crescent-like cavity between the two plate members, and that the use of solder or other brazing material for connecting the body member to the end plate is eliminated.

The device must be made in various sizes to accommodate different sizes of organs encountered in various patients, and the bulge 26 must be of such diameter, and so located with respect to length and shape, that it passes the internal os and fits snugly into the uterine cavity while the end plate contacts the vaginal part of the cervix.

The material of the coiled stem must have a moderate degree of flexibility in order to permit adaption to a malformed uterine tract, thereby eliminating the trauma which the sudden correction of a rigid stem would cause. Notwithstanding the deformation, the resiliency of the body member will constantly tend to straighten its axis, and such tendency may cause a lessening of the flexion and deformation of the tract in a great many patients. In many cases the degree of the deformation of the uterine tract may not be sufficient to call for correction, but it nevertheless will maintain patency of the entire uterine tract and prevent the collapsing of the uterine walls.

The entire device is made of a non-corrosive, nonoxidizing material; consequently it is not affected by uterine or vaginal secretions, regardless of the length of time the device may be applied *in situ*. However, indications call for a maximum duration of application of the menstrual cycle, after which the removal of the device is indicated.

The body being in the form of a helically coiled member, it may be inserted after prelimi-

nary sounding and dilatation into the uterus by rotating the body member in a clockwise direction with a suitable inserting instrument, and may be removed by rotating it in a contra-clockwise direction.

It has been found through extensive clinical investigation, that certain patients have considerable plicapalmata formation and folds of the cervical canal, which tend to obstruct and hinder the free passage of the coiled stem, when rotated into or removed from, the uterine tract. Furthermore, in surgical procedures, such as "Hyams Conization" or "Coagulation of the Cervix" or "Cautery," newly operated areas when brought in contact with the helical stem, may reach through the spacings of the stem and have a tendency to grow together. If this does occur, the shape of the tip of the stem is of paramount importance to permit, through contra-clockwise rotation, the removal of the stem. If the very end of the stem is tucked in, then a lacerating effect occurs, forcing the tip to cut circles into the mucosa located in the core of the spiral. If, however, the end of the wire is not tucked downward, but only in the height of the last coil with ample spacing at its end and all around it, then no harm can be created, as each succeeding coil follows the tract left by the previous coil.

As a further explanation, it would be clearest to imagine a helical spring cut at the tip without bending the wire end at all. Such a spiral would be the simplest to remove from the standpoint of contra-clockwise rotation. However, such spiral would do damage if it were rotated *in situ* in a clockwise rotation. The tissues and mucosa which would be found in the core of the spiral are pliable and have sufficient elasticity so that a mild squeezing action, resultant from the somewhat narrower spacing at the tip of the coil, would not result in laceration or trauma.

From the above, it is apparent that I have provided a pessary of novel and improved construction, composed of few parts, easily assembled, all connected together without the use of solder or other brazing material.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. As an improved article of manufacture, a pessary, comprising a helically wound filament 60 of flexible material forming the wall of a hollow body member, having a flaring base and having at its other end a bulged portion terminating in a substantially conical end portion, a centrally apertured dished disc formed with curled ears 65 at and around the aperture in the disc, the end coil at the other end of the body member extending through an aperture in said disc to the convex side thereof and being clenched over by said ears, and a second centrally apertured dished disc covering said end coil and ears, with its marginal edge secured to the first mentioned disc.

2. As an improved article of manufacture, a pessary, comprising a helically wound filament 75 of flexible material forming the wall of a hol-

low body member, having at one end a bulged portion terminating in a substantially conical end portion, a centrally apertured flanged dished disc formed with curled ears at and around the aperture in the disc, the end coil at the other end of the body member extending through an aperture in said disc to the convex side thereof and being clenched over by said ears, and a second centrally apertured dished disc covering said end coil and ears, with its marginal edge secured to the first mentioned disc by the flange of the first mentioned disc.
